UNITED STATES PATENT OFFICE.

PEARLY HUNT, OF CENTERVILLE, IOWA.

MOLDING OR FORMING MECHANISM.

No. 851,939.

Specification of Letters Patent.

Patented April 30, 1907.

Application filed June 25, 1906. Serial No. 323,359.

To all whom it may concern:

Be it known that I, PEARLY HUNT, a citizen of the United States, residing at Centerville, in the county of Appanoose and State of Iowa, have invented certain new and useful Improvements in Molding or Forming Mechanisms, of which the following is a specification, reference being had therein to the accompanying drawing.

This invention relates to improvements in molding mechanisms, and particularly to a mechanism used in the construction of a post or column.

The object of the invention is the provision of means for facilitating the construction of a cement or plastic column or post.

Another object of the invention is the provision of means for facilitating the construction of a composite post comprising a peculiarly constructed wooden core and a covering or shell of plastic material.

With these and other objects in view, the invention consists of certain other novel constructions, combinations, and arrangements of parts, as will be hereinafter fully described and claimed.

In the drawings: Figure 1 is a view in side elevation of a mechanism constructed in accordance with the present invention, part being shown in section. Fig. 2 is an end view of the mechanism. Fig. 3 is a fragmentary, vertical, longitudinal, sectional view of one end of the mechanism. Fig. 4 is a fragmentary, detail view of the mechanism, showing the locking means for securing the gage in an adjusted position. Fig. 4^a is a fragmentary, sectional view of one end of the slatted core. Fig. 5 is a fragmentary, perspective view of a column or post, comprising the slatted core or cylinder, with the same partly covered by a plastic shell, and illustrating the mode of supporting the post while in its green condition. Fig. 6 is a perspective view of the sides and bottom of the base-block molding device. Fig. 7 is a perspective view of the top plate of the base-block molding device. Fig. 8 is a vertical, sectional view of a molded base-block.

Referring to the drawings by reference numbers, 1 designates a plurality of base members, which are arranged transversely of the supporting platform 2. Secured to said base members upon one side of platform 2, are a

plurality of standards 3. Each standard is provided with a comparatively wide base 55 and top. The standards are curved intermediate their ends for producing overhanging portions 4, for the purpose hereinafter described.

The platform is provided at one end with a plurality of apertures 5, Fig. 3. A longitudinally adjustable standard 6 is supported upon the platform 2 at the end, which is provided with the apertures 5. The base web 7 of the standards 6 is provided preferably 65 with elongated apertures 8, which apertures 8 register with some of the apertures 5 of the platform 2. Suitable removable fastening means, as for instance, bolts 9, 9 are positioned within the registering apertures of the base-webs 7 of standard 6 and platform 2, whereby said standard 6 is securely retained in an adjusted position. It will be obvious that a slight, longitudinal adjustment of standard 6 may be obtained upon the platform 2 by loosening nuts 10, 10 of bolts 9, and after the adjustment has been obtained the standard 6 can be retained in its adjusted position by tightening said nuts 10 upon the bolts 9. If a considerable adjustment is desired for accommodating cores of different lengths, this can be done by entirely removing the bolts 9 and adjusting the standards 6 so as to register with the desired apertures, and then the bolts can be repositioned within the registered apertures and the nuts threaded tight thereon. It will be obvious that the adjustment of the standard is necessitated when slatted cores of different lengths are employed for producing columns 90 or posts of different lengths or heights. A bolt 11 is threaded into standard 6 near its upper end. The bolt 11 is provided with any suitable grip or handle 12 at its outer end, and on its inner end, there is formed a 95 tapering, penetrating point 13, Fig. 3. The tapering point 13 is normally seated within a socket or aperture formed in disk 14, which disk 14 is secured at the small end of the slatted core 15. A small disk 16 is fixedly secured to the threaded bolt 11, near the pointed end 13. The disk 16 is normally retained against the disk 14, when the core 15 is in the position shown in Figs. 1 and 3, thereby preventing said pointed end 13 from 100 being forced through or too far into the slat-

ted core 15. The pointed end 13 is formed substantially conical-shaped, so that the slatted core 15 is permitted to revolve freely thereon.

5 At the opposite end of the platform 2 to that carrying the standard 6, is secured a removable head block 17, which I will preferably hereinafter designate the "primary" standard, while the adjustable standard 6 10 will be designated, the auxiliary standard. The primary standard 17 is provided with a vertical body which is provided preferably with a pair of vertical bearing extensions or portions 18 at its upper end, while its base is 15 preferably formed with laterally extending flanges 19, 19, Fig. 2. The flanges 19 are provided with apertures, and suitable removable fastening means, as bolts 20, 20 are positioned within each of said flanges 19 for 20 fixedly securing the removable primary standard in a stationary position. It is not necessary to adjust the primary standard, as is the case with the auxiliary standard 6.

Removable caps 21 are positioned upon 25 the bearing extensions 18 and secured to said extensions by any suitable fastening means. Journaled between the caps 21 and the extensions 18 is rotary shaft 22. The shaft 22 is provided at its inner end with a squared 30 shoulder 23, which is normally positioned within a similarly constructed aperture formed in the disk 24, which disk is positioned in the largest end of the slatted core 15. By reason of the squared structure of 35 the inner end 23 of the shaft 22 and the recess or disk 24, when rotary movement is imparted to the shaft 22, similar movement will be imparted to the slatted core. A disk 25 is fixedly secured to the shaft 22 contiguous 40 to the squared end 23 and is adapted, like disk 16, to engage a disk, when the core is in its normal position, Fig. 1. A shoulder 26 is formed upon shaft 22, and is of greater diameter than the journals or apertures 45 formed in the primary standard 17 by means of the extensions 18 and caps 21. The shoulder 26 prevents outward movement of shaft 22 upon the primary standard 17. Rotatory movement may be imparted to said 50 shaft 22, by applying power to the belt wheel 29, which wheel is fixedly secured near the outer end of shaft 22, or if it is desired, an ordinary crank shaft, shown by dotted lines 30, may be secured to the squared, outer end 31 55 of shaft 22. It will be obvious that either mechanical or manual power may be utilized for rotating the slatted core.

If it is desired to remove the slatted core 15 from the threaded bolt 11 and shaft 22, 60 this may be accomplished by threading the bolt 11 outward upon the auxiliary standard 6. If it is desired to position the slatted core 15 upon bolt 11 and shaft 22, the same may be done by rotating said bolt sufficient 65 to permit the core to pass between the inner

ends of the bolt 11 and shaft 22, and after said core has been so positioned, the ends of said bolt and shaft may be seated within the respective recesses or sockets, as hereinbefore described.

The slatted core 15 is an essential element 70 of the mechanism, as well as an essential part of the finished column or post, see Fig. 5. The slatted core comprises preferably a plurality of disks, and in the present instance, I have illustrated the larger disk 24 secured at one end of the core and the smaller disk 14 secured at the other end of the core. An intermediate disk 33 is positioned within the slatted core, preferably near the middle 80 thereof. The slats 32 are fixedly secured to the disks by any suitable fastening means, as for instance, nails 34. After the plastic material, as for instance, cement, has been placed upon the slatted core, as hereinafter 85 described, and if it is desired to remove the core with its coating of cement, and support the same until the cement has completely dried, this can be accomplished by drawing the longitudinally sliding handles 35 outward 90 through the medium of their hooked ends 36.

There is a handle 35 positioned in the slatted core, at each of its ends. Blocks 35' are secured to one of the slats 32 contiguous to the end disks. Each block 35 is provided 95 with a longitudinal groove 36', Fig. 4a, and each end disk is provided with a transverse groove 37. The handles 35 are slidably seated within the grooves 36' and 37. By grasping the grip or hooked end 36 of the handles, 100 the handles may be partly or entirely withdrawn. However, as the post or column nears completion, and before the ends are entirely sealed, it is desirable to partly withdraw the handles 35, and when the post or 105 column is ready to be removed from the machine, the operator can lift said post, through the medium of said handle, from said machine and support the post in any suitable manner, as for instance, shown in Fig. 5. It 110 will be seen upon referring to this figure that the dotted lines designate the handles 35, and said handles are resting upon vertical supports 38. The grips or hooked ends 36 of the handles also prevent the post from 115 normally sliding off or being displaced from the supports 38. The peculiar structure of the slatted core for receiving the handles is an essential part of the finished composite post or column.

The wide, upper ends 4 of the curved supports 3 are provided for supporting a flat gage 39. Of course, the gage need not necessarily be flat in structure, but I preferably use a flat gage, which is provided with 125 transverse, elongated slots 40. Each slot is formed in said gage 39 contiguous to the curved supports 3; the upper end 4 of the curved supports 3 overhanging the slatted core 15. Secured to each of the ends 4 of the 130

curved supports 3 is a spring locking member 41. The locking member 41 is fixedly secured at one end to the curved support 3, and its outer end is looped around and provided with a bearing portion 42, which exerts sufficient pressure against the gage 39 to retain it under normal conditions in an adjusted position. By drawing out on the looped, spring end of the fastening member 41, the gage 39 can be slid upward or lowered on the ends 4, so as to control the thickness of the cement, as it is placed upon the slatted core. The cement is placed on the core preferably by means of a trowel. Before any cement is placed on the slatted core, said core is preferably soaked, for the reason that if it was not soaked in water before cement was applied, the slats would, undoubtedly, swell as the cement dried, and thereby be liable to crack the post or column. By soaking or wetting the slatted core, said core dries synchronously with the cement, and obviates the possibility of the post or column cracking. Removably secured at each end 25 of the gage 39, is a finger 43. The finger 43 is secured to the gage 39 by any suitable fastening means, as for instance, screws 44. The gage 39 may be employed for forming posts or columns for different designs, as by reversing the position of the gage, differently constructed; longitudinal edges may be placed contiguous to the slatted core. Therefore, it is desirable to have the fingers 43 extend upon opposite sides or edges of the 35 gage 39. These fingers remove any extra cement overhanging or projecting beyond the ends of the post or column. Transverse notches or grooves 45 are formed upon each of the longitudinal edges of the gage 39, whereby annular beads 46, Fig. 5, are formed upon the post or column. Metallic markers 47 are seated within cut-out portions 48, Fig. 4, contiguous to one of the longitudinal edges, and each marker is preferably provided with an elongated slot 49, within which slot is positioned a screw, or any suitable fastening means, whereby each marker is adjustable within the slot 49, so that annular grooves 50 of different depths, Fig. 5, may be 45 formed in the post or column.

The base-block mold 51 comprises four sides hinged together, as at 52, and one of said sides is provided with elongated notches 52, Fig. 6, within which are adapted to be secured spring fastening members 53, which members 53 are fixedly secured at one end to one of the sides. These spring locking members secure the sides in their normal closed position, but it will be obvious that said sides 55 may be moved apart when desired. A removable bottom 54 is positioned between the sides of the mold, and a tapering extension 55 is fixedly secured to the upper portion of the bottom 54. This extension 55 is preferably semi-spherical in shape, and is adapted

to form a similarly constructed recess in the finished base-block 56, Fig. 8. A top plate 57 is provided with a central opening 58. The opening 58 may be round, as shown in Fig. 7, or may be, preferably, squared at the 70 option of the constructor. The plastic material is placed in the mold and tamped, and then the plate 57 is placed upon the sides and the opening 58 is filled. When it is desired to place the green block upon a support and again use the mold 51, this can be accomplished by inverting the mold upon the top plate 57, removing the bottom 54, and again reversing the position of the mold upon a suitable pallet. Subsequently, the top plate 80 75 85 90 95 100 105 110 115 120 125 130

57 may be removed, and then the hinged sides. It is desirable, however, to form a base-block with a sphere 59 positioned within the semi-spherical recess formed by the extension 55. When the base-block is in use, the lower portion of the sphere 59 is positioned in the semi-spherical recess formed in a support 60. The extension 61, formed by the aperture 58 in the top plate 57, is positioned within a similarly constructed aperture formed in the base or larger end of the finished post or column. The recess within which the extension 61 of the base-block is positioned, is formed similar to recess 62, Fig. 5, which recess 62, is formed in the upper end of the post or column. The base-block 56 comprises a body portion provided on its upper portion with an extension 61, and on its lower portion with a sphere 59. The sphere 59 is preferably separately molded from the body of the base-block, and is inserted and integrally secured to the body after the body has been molded and while yet in its green state.

The recess and groove of disk 24 and the recess of disk 14 assist in securing the plastic coating or shell upon the core of the finished post or column, as the cement will be positioned therein, and act, when dried, as a lock for the plastic coating or shell.

When the core is coated with plastic material, the disks, which may be of any shape or configuration, are not covered. It will, therefore, be obvious that a recess or opening, as for instance, 62, Fig. 5, will be formed in each end of the finished post. Of course, in the present instance, I have preferably employed disks, and have so described the members 16 and 25.

In view of the foregoing description, it will be understood that primary standard 17 and auxiliary standard 6 must be spaced apart a sufficient distance to permit a green post or column to be removed from between the same without marring, or otherwise injuring said post or column.

What I claim is:

1. In a mechanism of the class described, the combination with a support, of a stationary and an adjustable standard carried by

4. said support, a core positioned between and supported upon said standards, and a vertically adjustable gage positioned contiguous to said core.
5. 2. In a mechanism of the class described, the combination of a support, a revoluble core carried by said support, a gage carried by said support, and spring locking means carried by said support and securing said gage in an adjusted position. 70
6. 3. In a mechanism of the class described, the combination of a platform, a longitudinal adjustable standard secured at one end of said platform, a stationary standard secured at the opposite end of said platform, a slatted core positioned between said standards, means carried by and connecting and supporting said core upon said standards, and means for rotating said core. 75
7. 4. In a mechanism of the class described, the combination of a platform, standards carried by said platform, a threaded member carried by one of said standards, a rotary shaft carried by the other standard, a core supported upon said threaded and rotary members, and means for rotating said core. 80
8. 5. In a mechanism of the class described, the combination of a platform, transverse base members supporting said platform, supports secured to said base members, an adjustable gage secured to the upper ends of said supports, and a core supported upon and positioned above said platform and contiguous to said gage. 85
9. 6. In a mechanism of the class described, the combination of curved supports, a vertically adjustable gage secured to the upper end of said supports, means for locking said gage in an adjusted position, a revoluble core positioned contiguous to said gage, and means for revolving said core. 90
10. 7. In a mechanism of the class described, the combination with a support, of a gage carried by said support, said gage comprising a flat body provided with notches and transverse, elongated apertures, fingers secured to the ends of said gage, means positioned within the elongated apertures and normally securing said gage in an adjusted position, and a revoluble core carried by said support and positioned contiguous to said gage. 95
11. 8. In a mechanism of the class described, the combination with a support, of a flat gage carried by said support, said gage provided with transverse elongated apertures, spring locking means positioned within said apertures and normally securing said gage in an adjusted position, removable fingers secured to the ends of said gage, said gage provided with a notched edge, a marker secured to said gage, and a core positioned contiguous to said gage. 100
12. 9. In a mechanism of the class described, the combination with a support, of a revoluble core carried by said support, a gage posi- 105
13. tioned contiguous to said core, said gage provided with a recess, and an adjustable marker positioned within said recess and extending from one of the edges of said gage. 110
14. 10. In a mechanism of the class described, the combination with a platform, of standards positioned at the ends of said platform, a removable core carried by said standards, curved supports positioned contiguous to said platform, said supports provided with upper ends overhanging said core, a longitudinally extending gage engaging the overhanging ends of said supports and positioned contiguous to said core, and means for rotating said core. 115
15. 11. In a mechanism of the class described, the combination with a support, of a core carried by said support, a vertical support positioned contiguous to said core, the upper end of said vertical support overhanging said core, a removable gage carried by the upper overhanging end of said vertical support, means securing said gage to said vertical support, and means for imparting movement to said core. 120
16. 12. In a mechanism of the class described, the combination with a support, of a core carried thereby, said core comprising a plurality of disks of varying diameters, slats secured to said disk, a slidable handle positioned within each end of said core, and means for rotating said core. 125
17. 13. In a mechanism of the class described, the combination with a support, of a slatted core carried by said support, said core provided at each end with a longitudinal grooved block and with a grooved disk, a handle seated within the grooves of said block and disk, said handle provided with a hooked end. 130
18. 14. In a mechanism of the class described, the combination with a support, standards carried by said support, one of said standards provided with a rotary shaft, the other standard provided with an adjustable bolt, and a core supported upon said shaft and bolt. 135
19. 15. In a mechanism of the class described, the combination with a support, of standards carried by said support, rotary members carried by said standards, a disk secured to each of said members, and a core mounted upon said members and in engagement with said disks. 140
20. 16. In a mechanism of the class described, the combination with a support, a rotatable core carried by said support, of a vertical support positioned contiguous to said first mentioned support, said vertical support having its upper end overhanging said core, a gage engaging the upper end of said support, and locking means for securing said gage in different positions upon said vertical support. 145
21. 17. In a mechanism of the class described, the combination with a support, a core carried by said support, of a vertical support posi- 150

- tioned contiguous to said first mentioned support, an adjustable gage engaging said vertical support and positioned contiguous to said core, and means for securing said gage 5 in different positions upon said vertical support.
18. In a mechanism of the class described, the combination with a support, of a standard carried by said support, an adjustable bolt or member carried by said standard, another standard carried by said support, a rotatable shaft carried by said last mentioned standard, a core positioned upon and supported between said bolt and shaft, 15 means for locking said core against independent rotary movement with respect to said shaft, and means for imparting rotary movement to said shaft and core.
19. In a mechanism of the class described, 20 the combination with a support, of standards carried by said support, a core positioned between said standards, means carried by one of said standards and co-operating with said core for imparting rotary movement thereto, 25 and movable means carried by the other standard for supporting one end of said core and permitting said core to be removed from between said standards.
20. In a mechanism of the class described, 30 the combination of standards, a core positioned contiguous to said standards, means supporting one end of said core upon one of said standards, a shaft rotatably mounted upon the other standard, said shaft provided 35 with a squared inner end and a disk positioned upon said shaft contiguous to said squared end, said squared end positioned within a portion of said core and the disk in engagement with said core.
21. In a mechanism of the class described, 40 the combination with a support, of a pair of standards carried by said support, a core positioned between said standards, means supporting one end of said core upon one of 45 said standards, a rotatable shaft supported upon the other standard, said shaft provided with a shoulder and a squared end, and a disk positioned upon said shaft between its squared end and shoulder, and said squared 50 end in engagement with one end of said core.
22. In a mechanism of the class described, 55 the combination with a support, of standards carried by said support, a core positioned between said standards, means for rotating said core, and means for fixedly securing said core upon said standards.
23. In a mechanism of the class described, 60 the combination with a support, of standards carried by said support, a revoluble core, means carried by one of said standards for rotating said core, and means for removably securing said core upon said standards.
24. In a mechanism of the class described, 65 the combination with a support, a rotatable core carried by said support, of a gage carried by said support, and a finger in engagement with each end of and extending upon opposite sides of said gage.
25. In a mechanism of the class described, 70 the combination with a support, of a core carried by said support, a gage carried by said support, an adjustable marker carried by and adapted to be extended beyond one edge of said gage.
26. The combination with a support, a rotatable core carried by said support, of an auxiliary support positioned contiguous to said first mentioned support, an adjustable gage in engagement with said last mentioned 75 support and positioned contiguous to said core, and locking means for adjustably securing said gage in a fixed position upon said auxiliary support.
27. In a mechanism of the class described, 80 the combination with a support, a core carried by said support, of an auxiliary support positioned contiguous to said first mentioned support, a gage in engagement with said auxiliary support and positioned contiguous to 85 said core, and spring-locking means securing said gage upon said auxiliary support.
28. In a mechanism of the class described, 90 the combination with a support, a core carried by said support, a gage, means supporting said gage contiguous to said core, of a removable finger in engagement with one end of said gage, and means securing said finger to said gage.
29. In a mechanism of the class described, 95 the combination with a support, of standards carried by said support, a core positioned contiguous to said standards, means supporting one end of said core upon a standard, an adjustable member carried by the 100 other standard, said member supporting one end of said core, and said member adapted to be adjusted for permitting removal of said core.
30. In a mechanism of the class described, 105 the combination with a support, of a core carried by said support, means for rotating said core, said core comprising solid disks, slats spaced apart and secured to said disks, a support positioned contiguous to said first 110 mentioned support, a removable gage secured to said last mentioned support, and locking means for securing said gage in an adjusted position upon said last mentioned support.
31. In a mechanism of the class described, 115 the combination with a support, of a removable standard carried by said support, said standard being capable of adjustment upon said support, fastening means for securing 120 said standard in an adjusted position, a core positioned contiguous to said support, means for supporting one end of said core upon said support, and means for supporting the other end of said core upon said standard.

32. In a mechanism of the class described, the combination with a support, of a core carried by said support, an auxiliary support, a gage in engagement with said auxiliary support, a yieldable member secured to and locking said gage in an adjusted position upon said auxiliary support.

In testimony whereof I hereunto affix my signature in presence of two witnesses.

PEARLY HUNT.
